(57) **CLAIM**

The ornamental design for an electronic water sensor as shown and described.

DESCRIPTION

FIG. 1 is a bottom perspective view of an embodiment of the electronic water sensor;

FIG. 2 is a top perspective view of the electronic water sensor of FIG. 1;

FIG. 3 is a bottom view of the electronic water sensor of FIG. 1;

FIG. 4 is a top view of the electronic water sensor of FIG. 1;

FIG. 5 is a side view of the electronic water sensor of FIG. 1;

FIG. 6 is a side view of the electronic water sensor opposite of FIG. 5;

FIG. 7 is a front view of the electronic water sensor of FIG. 1;

FIG. 8 is a rear view of the electronic water sensor of FIG. 1;

FIG. 9 is an exploded view of the electronic water sensor of FIG. 1; and,

FIG. 10 is a partial exploded view of the electronic water sensor of FIG. 1.
